UNITED STATES PATENT OFFICE.

JESSE J. EVANS, OF GLASSPORT, PENNSYLVANIA.

METALLIC TIE.

SPECIFICATION forming part of Letters Patent No. 779,269, dated January 3, 1905.

Application filed September 9, 1904. Serial No. 223,822.

To all whom it may concern:

Be it known that I, JESSE J. EVANS, a citizen of the United States of America, residing at Glassport, in the county of Allegheny and State of Pennsylvania, have invented certain new and useful Improvements in Metallic Ties, of which the following is a specification, reference being had therein to the accompanying drawings.

This invention relates to certain new and useful improvements in metallic ties, and has for its object the provision of novel means whereby rails may be secured to the ties, dispensing with the use of spikes, chairs, clamps, and the like.

The present invention has for its object to provide a metallic tie formed of two like sections which may be easily rolled and securely fastened together for the purpose hereinbefore designated.

My invention still further contemplates to provide a metallic rail-fastener which will be extremely simple in construction, strong, durable, comparatively inexpensive to manufacture, and highly efficient in its use.

With the above and other objects in view the invention consists in the novel construction, combination, and arrangement of parts to be hereinafter more fully described, and particularly pointed out in the claims.

In describing the invention in detail reference is had to the accompanying drawings, forming a part of this application, and wherein like numerals of reference indicate like parts throughout the several views, in which—

Figure 1 is a side elevation of my improved tie, showing a pair of rails secured thereto, the latter being illustrated in section. Fig. 2 is a fragmentary perspective view of my improved tie. Fig. 3 is an end view of a pair of ties, showing the rail in side elevation.

In the drawings the rails are represented by numerals 1, and the tie-sections are designated by reference-numerals 2 3. These tie-sections are of the channel-bar construction and are secured together so as to form a rein-

forcing-web portion 4 and outwardly-extending base-flanges 5 5 and tread-flanges 6 6. The tread-flanges 6 are sheared, as shown at 7, forming fastening-lugs 8, which serve to secure and partially embrace the base of the rail. An opening is formed through the web 4, as shown at 9, for the reception of a key 10, having an opening 11 formed therein for the reception of a locking-wedge 12.

It will be noted that the base-flanges 5 are of greater width than the tread-flanges 6 of the tie and that by this manner a more substantial and cheaper construction is obtained than by employing an I-beam. Furthermore, the rails are fastened in such a manner as will permit the same to expand and contract.

The many advantages obtained by the use of my improved construction will be readily apparent from the foregoing description, taken in connection with the accompanying drawings.

It will further be noted that various changes may be made in the details of construction without departing from the general spirit of my invention.

Having fully described my invention, what I claim as new, and desire to secure by Letters Patent, is—

1. In a metallic tie, the combination of similar channel-bars, the base-flange being of greater width than the tread-flange, means to secure said channel-bars together, and lugs sheared from the said tread-flange extending to the sides thereof, substantially as described and for the purpose set forth.

2. In a metallic tie, the combination of two channel-bars, each having a horizontal tread-flange at its upper edge and a horizontal base-flange at its lower edge, said bars being provided with registering openings in their webs, keys passing through said openings, locking-wedges passing through said keys and means carried by said tread-flanges for securing rails thereto.

3. In a metallic tie, the combination of two connected channel-bars placed with their web

portions in contact and constituting an I-beam, said web portions being formed with registering openings, keys passing through said openings, locking - wedges passing through said keys, said channel-bars being each formed with lugs sheared from the upper flange thereof, extending to the edge of the flange.

In testimony whereof I affix my signature in the presence of two witnesses.

JESSE J. EVANS.
